(57) **CLAIM**

We claim the ornamental design for a scoop bottle neck, as shown and described.

DESCRIPTION

FIG. 1 is a top, front and right side perspective view of a scoop bottle neck showing the new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a top perspective thereof showing a scoop positioned with the neck; and,

FIG. 8 is a cross-sectional view thereof, taken along the line 8-8 in FIG. 7.

The broken lines shown in the drawing views are included for the purpose of showing environmental structure that forms no part of the claimed design.
